UNITED STATES PATENT OFFICE

99,856

DESIGN FOR A SHOE UPPER MATERIAL

Claude H. Daniels, Wellesley Hills, Mass.

Application March 11, 1936, Serial No. 61,568

Term of patent 14 years

To all whom it may concern:

Be it known that I, Claude H. Daniels, a citizen of the United States of America, residing at Wellesley Hills, in the county of Norfolk and Commonwealth of Massachusetts, have invented a new, original, and ornamental Design for Shoe Upper Material, of which the following is a specification, reference being had to the accompanying drawing, forming part thereof.

The drawing is a plan view of a piece of shoe

upper material showing my new design which is formed by perforating the material; the ornamentation shown thereon may be extended over any desired area.

I claim:

The ornamental design for shoe upper material, substantially as shown and described.

In testimony whereof I affix my signature.

CLAUDE H. DANIELS.
